(57) CLAIM

The ornamental design for a heart-shaped brush, as shown and described.

DESCRIPTION

FIG. 1 is a top plan view of a heart-shaped brush showing
my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a perspective view thereof.

The claimed heart-shaped brush is used for cleaning shoes and clothing.
